HYDROLYSIS OF N-SUBSTITUTED AMIDES

William L. Mosby, North Plainfield, and Saul R. Buc, Easton, N.J., assignors to General Aniline & Film Corporation, New York, N.Y., a corporation of Delaware

No Drawing. Application July 2, 1956
Serial No. 595,139

7 Claims. (Cl. 260—515)

This invention relates to the hydrolysis of N-substituted amides of acenaphthene carboxylic acids and relates more particularly to the hydrolysis of acenaphthene carboxamides to produce their corresponding acids.

Heretofore, in the hydrolysis of N-substituted amides of acenaphthene carboxylic acids the hydrolytic medium employed comprised ethylene glycol and potassium hydroxide. However, the results obtained by the use of this hydrolytic medium were not satisfactory as to yield or purity. The amount of final product obtained fell 12-13% short of quantitative yield and was quite impure. It is, accordingly, an important object of this invention to provide a novel process for the hydrolysis of acenaphthene carboxamides to their corresponding acids wherein improved yield and quality of product is obtained.

Another object of this invention is the provision of an improved process for hydrolyzing acenaphthene carboxamides to their corresponding acids by the use of an aqueous hydrolytic medium containing a surface active agent and an excess of alkali.

Other objects of this invention will appear from the following detailed description and claims.

The process of the instant invention may be employed in the hydrolysis of any N-substituted amide of acenaphthene carboxylic acid. However, this invention will be particularly described in connection with the hydrolysis of acenaphthene 5-carboxamide and acenaphthene 5,6-carboxamide to their corresponding acids, namely 5-acenaphthoic acid and 5,6-acenaphthalic acid, respectively, since these are valuable intermediates for dye-stuffs, fluorescing agents and pharmaceuticals. For example, 5,6-acenaphthalic acid may be oxidized in substantially quantitative yield to 1,4,5,8-tetracarboxylic acid ("Tetra Acid") which is useful in the preparation of vat dyes such as Indanthrene Brilliant Orange GR, Indanthrene Scarlet GG, Indanthrene Bordeaux RR and the like.

In accordance with this invention, the N-substituted amide, such as acenaphthene 5-carboxamide and acenaphthene 5,6-carboxamide, are hydrolyzed by suspending the amide in water containing a slight excess of caustic and a trace of wetting agent or detergent, and the suspension heated under superatmospheric pressure for 4 to 6 hours at a temperature of about 200° C. The solution obtained is treated with a suitable acid, such as hydrochloric acid or sulfuric acid, for example, to produce the corresponding organic acid. If desired, a few steel balls may be added to the suspension for the purpose of breaking up any lumps therein and thus facilitating hydrolysis.

Any suitable alkali- and heat-stable wetting agent or detergent may be employed in the process of the instant invention such as, for example, the diethyl ester of sulfosuccinic acid (Aerosol OT), alkyl benzene sulfonates, e.g. dodecyl benzene sulfonates, Igepon T types (N-acyl-N-methyltaurines), Igepal types (polyoxyethylated alkyl

2

phenols), long chain alcohol sulfates and Alipals (sulfated polyoxyethylated alkyl phenols).

The instant invention will be more clearly understood from the following examples which are merely illustrative and in no way limitative.

Example I

To 234 grams of acenaphthene 5-carboxamide were added about 1 gram of Aerosol OT, 38 grams of 98% pure sodium hydroxide and 600 cc. of water. A few $\frac{3}{8}$ -inch steel balls were added and the mixture shaken in a steel bomb for 4 hours at 200° C. The clear dark-brown solution obtained was adjusted to approximately pH 7 with dilute hydrochloric acid, charcoaled and filtered. Acidification of the filtrate, filtering, washing and drying gave a quantitative yield of pure white 5-acenaphthoic acid.

Example II

20 A mixture of 156 grams of acenaphthene 5,6-dicarboxamide, 58 grams of potassium hydroxide, 1 gram of Aerosol OT and 600 cc. of water, to which were added a few $\frac{3}{8}$ -inch steel balls, was shaken in a steel bomb for 6 hours at 200° C. The dark-brown solution obtained was adjusted to approximately pH 7 with dilute hydrochloric acid, charcoaled and filtered. Acidification, filtering, washing and drying gave an almost quantitative yield of nearly white 5,6-acenaphthalic acid.

It is to be understood that the foregoing detailed description is given merely by way of illustration and that many variations may be made therein without departing from the spirit of our invention.

Having described our invention what we desire to secure by Letters Patent is:

35 1. Process for preparing acenaphthene carboxylic acids, which comprises suspending an N-substituted amide of acenaphthene carboxylic acid, selected from the group consisting of acenaphthene 5-carboxamide and acenaphthene 5,6-carboxamide, in water containing an excess of caustic and a small amount of alkali- and heat-stable detergent, heating said suspension at a temperature of about 200° C. for from four to six hours, and acidifying the resulting solution.

40 2. Process for preparing acenaphthene carboxylic acids, which comprises suspending an N-substituted amide of acenaphthene carboxylic acid, selected from the group consisting of acenaphthene 5-carboxamide and acenaphthene 5,6-carboxamide, in water containing an excess of caustic and a small amount of alkali- and heat-stable detergent, heating said suspension at a temperature of about 200° C. for from four to six hours, and acidifying the resulting solution by adding thereto a mineral acid so as to cause acenaphthene carboxylic acid to precipitate.

45 3. Process for preparing acenaphthene carboxylic acids, which comprises suspending an N-substituted amide of acenaphthene carboxylic acid, selected from the group consisting of acenaphthene 5-carboxamide and acenaphthene 5,6-carboxamide, in water containing an excess of caustic, selected from the group consisting of sodium hydroxide and potassium hydroxide, and a small amount of alkali- and heat-stable detergent, heating said suspension at a temperature of about 200° C. for from four to six hours, and acidifying the resulting solution by adding thereto a mineral acid so as to cause acenaphthene carboxylic acid to precipitate.

50 4. Process for preparing 5-acenaphthoic acid, which comprises forming a mixture of acenaphthene 5-carboxamide, an excess of sodium hydroxide, a small amount of alkali- and heat-stable detergent and water, heating said mixture under pressure and with agitation for 4

hours at 200° C., and precipitating 5-acenaphthoic acid from the resulting solution by adding hydrochloric acid to said solution.

5. Process for preparing 5,6-acenaphthalic acid, which comprises forming a mixture of acenaphthene 5,6-dicarboxanilide, an excess of potassium hydroxide, a small amount of alkali- and heat-stable detergent and water, heating said mixture under pressure and with agitation for 6 hours at 200° C., and precipitating 5,6-acenaphthalic acid from the resulting solution by adding hydrochloric acid to said solution.

10 6. Process for preparing 5-acenaphthoic acid, which comprises forming a mixture of acenaphthene 5-carboxanilide, an excess of sodium hydroxide, a small amount of alkali- and heat-stable detergent and water, heating said mixture under pressure and with agitation in the presence of steel balls for 4 hours at 200° C., and precipitating 5-acenaphthoic acid from the resulting solution by adding hydrochloric acid to said solution.

15 7. Process for preparing 5,6-acenaphthalic acid, which

comprises forming a mixture of acenaphthene 5,6-dicarboxanilide, an excess of potassium hydroxide, a small amount of alkali- and heat-stable detergent and water, heating said mixture under pressure and with agitation in the presence of steel balls for 6 hours at 200° C., and precipitating 5,6-acenaphthalic acid from the resulting solution by adding hydrochloric acid to said solution.
